UNITED STATES PATENT OFFICE.

LYMAN G. CRUM, OF JAMESTOWN, NORTH DAKOTA.

GRIPPING MEANS FOR JOB-PRESSES.

1,251,868.

Specification of Letters Patent.

Patented Jan. 1, 1918.

Application filed September 15, 1917. Serial No. 191,611.

To all whom it may concern:

Be it known that I, LYMAN G. CRUM, a citizen of the United States, residing at Jamestown, in the county of Stutsman and State of North Dakota, have invented certain new and useful Improvements in Gripping Means for Job-Presses, of which the following is a specification, reference being had to the accompanying drawings.

10 This invention relates to paper grippers used on job printing presses, and particularly to that class of grippers in which the grippers are mounted upon a base member and are adjustable toward or from each

15 other along said base member.

With the paper grippers now in use on job presses, it is common for the operator to place a rubber band or cord, or a plurality of these bands or cords around the grippers 20 so as to extend across from one gripper to the other, but this is ineffective as often-times when the ink is sticky, the paper pulls through these bands and the bands or cords do not hold the paper firmly.

25 The general object of my invention is to provide a paper gripping device in which the grippers are provided with adjustable paper holding fingers, which may be moved into or out of parallel relation to the grippers, that is, into or out of operative position, and which are slideable toward or from each other along the length of each gripper, so as to adjust the fingers into proper relation.

35 A further object is to provide improved means for mounting the fingers upon the grippers, and improved means for holding the fingers in adjusted positions.

40 A further object of the invention is to provide a device of this character, which is so constructed that it may be used in place of the ordinary grippers without in any way changing the construction of the press.

45 Other objects will appear in the course of the following description.

My invention is illustrated in the accompanying drawings, wherein:—

Figure 1 is a top plan view of my improved paper gripper;

50 Fig. 2 is a fragmentary sectional view of the paper gripper applied to a press;

Fig. 3 is a section on the line 3—3 of Fig. 1;

55 Fig. 4 is a section on the line 4—4 of Fig. 1;

Fig. 5 is a perspective view of a portion of one of the slides which carry gripping fingers;

Fig. 6 is a face elevation of the construction shown in Fig. 5;

Fig. 7 is a perspective view of the base member and one of the grippers; and

Fig. 8 is a fragmentary plan view of one of the grippers showing the manner in which the wire is tensioned.

Fig. 9 is a perspective view of the slide 20 and its finger;

Fig. 10 is a sectional view of a slide with the finger in elevation.

Referring to these figures, 10 designates the base, as it may be termed, comprising a longitudinally extending bar or rail, which is longitudinally slotted as at 11, this slot extending nearly to the ends of the bar or rail. This slot permits the rail to be held upon the cross bar A of the press, as illustrated in Fig. 2, by means of bolts 12. Also extending longitudinally along the face of the rail, for its entire distance, is a groove 13. The inner face of the base 10 is provided at its ends with outwardly projecting portions 14 and stretched tightly over these portions 14 and extending longitudinally along the inner face of this bar or rail 10 in spaced relation to the greater portion of this inner face is a very taut wire 15. This wire is ordinarily fairly taut but may be placed under even greater tension by means of a tightening device comprising a rod 16 passing through an aperture in the middle portion of the rail or bar 10, this rod having an eye 17 at one end which engages around the wire 15, this rod being connected to a lever 18 pivotally mounted in a recess 19 formed in the face of the bar 10 adjacent its outer corner. When this lever 18 is turned in one direction, it will slacken the tension of the wire 15 and when turned in the other direction it will draw the middle of the wire inward, thus increasing its tension. When the lever is turned in a direction to increase the tension of the wire, it will be disposed in a recess as shown in Fig. 1 and, therefore, locked until the lever is turned manually in the opposite direction to decrease the tension of the wire.

The face of the bar 10 is formed with a groove and sliding within this groove is a slide 20, as illustrated in Figs. 9 and 10. This slide has a longitudinally extending

tongue 21, which engages within the groove and the outer face of the slide is formed with outwardly projecting ears 22 and is longitudinally grooved as at 23, this groove extending nearly to the ends of the slide, but not quite, so as to leave webs 24. The wire 15, as illustrated in Fig. 10, passes over these members 24 and then in behind the butt end of a finger 25, which is pivoted between the ears 22. It will thus be seen that the wire will press against the butt end of the finger and that as this butt end is flat, the wire will act to resist any movement of the finger in one direction or the other. In other words, when the finger is turned parallel to the bar 10, the wire will resist any opening of the finger, and when the finger is extended perpendicularly to the bar 10, the wire will also resist any closing of the finger. Inasmuch as the wire passes over the slide 20, it follows that when the wire is tightened by operating the fastening device heretofore described, the wire will be drawn taut across the slide 20 and will hold this slide against accidental longitudinal movement. There are two of these slides 20 mounted upon the bar 10, one on each side of the middle of the bar as illustrated in Fig. 1, and these slides may be adjusted longitudinally along the whole extent of the bar 10 and the fingers may be turned out perpendicularly to the bar or in parallel relation to the bar, as it may be desired.

Slidably mounted upon the bar 10 are the outwardly extending end pieces or grippers 26, one of which is illustrated in Fig. 7 in conjunction with the bar 10. As illustrated in Fig. 1, there are two of these grippers and each of these grippers is formed of a thin strip of wood or metal having a tongue at its butt end upon its inside face, this tongue being designated 27 and sliding within the groove 13. A bolt 28 passes through each of these grippers and into the slot 11 and by loosening this bolt, the gripper may be slid toward or from the middle of the bar 10 and then by tightening the bolt the gripper is held in its adjusted position. Each of these grippers is also provided with a pair of sliding and pivoted fingers. To this end each of these grippers is formed at its ends with the projecting portions 29, and a wire 30 is tightly stretched over these projecting portions and in spaced relation to the inside edge of the corresponding gripper. The inside edge of the gripper is formed with a groove 31 and the middle of the wire is connected to a tightening device, which is constructed in exactly the same manner as the tightening device previously described and consists of a rod 16 and a lever 18 disposed in a recess in the upper edge face of the gripper near the outer corner so that when the lever is turned in one direction, the wire will be tightened and when turned

in the other direction, the wire will be slackened.

Operating upon the edge face of the gripper is a slide 32, as illustrated in Figs. 5 and 6. This slide 32 is formed with a longitudinally extending tongue 33 adapted to engage in the groove 31 and the outer edge of the slide is grooved as at 34 for the reception of the wire 30. The under face of the slide is cut away and pivotally mounted upon this under face is a finger 35. Bearing against a shoulder 36 on the slide is a spring 37, which is outwardly bowed and bears against the butt end of the finger 35 and against one side face of the finger, when the finger is turned to a position parallel to the edge of the gripper. This spring 37 acts to yieldingly hold the finger in a projected or a retracted position in the same manner as a spring in a knife blade holds a knife blade in a projected or retracted position. It will be noted from Fig. 3 that the fingers 35 are disposed in the same plane as the inner face of the grippers upon which they are mounted and hence the fingers 25 must be deflected as at 38, so as to bring these fingers into the same plane, so that all of the fingers when in use will lie flat upon the paper.

In the practical use of this device, it will be seen that either of the gripping fingers 25 may be turned out to a position at right angles with the base bar 10 or turned into a position parallel to the base bar, or that either of the fingers 35 may be turned out perpendicularly to the grippers 26 or turned parallel thereto and that all of the gripping fingers may be used at one time or certain of the gripping fingers turned into inoperative position. Thus in Fig. 1, I show the lateral gripping fingers 35 turned to a projected position and the fingers 25 turned to an inoperative position. Furthermore it will be obvious that the slides holding the gripping fingers may be shifted along the bar 10 or along the grippers 26 so as to bring the gripping fingers exactly in adjusted position for proper operation. The bar 10 is so formed that it may be used in place of the ordinary base bar supporting the ordinary gripping fingers and may be applied to any job press in the usual manner. It will be seen that this device is very simple, that it is relatively cheaply constructed and that it will be thoroughly effective for the purpose intended, that is, for preventing the paper sticking to the inked type after an impression has been made. It will be obvious that as the gripping fingers are adjustable, they may be arranged to engage any desired size of sheet or of card which is to be printed. Of course the sheet of paper which is to be printed is centered in the usual manner by gage pins. Various minor changes may be made in the details of construction and arrangement of parts of this device, without

departing from the spirit of the invention.

Having thus described my invention, what I claim is:—

5. 1. A paper gripping device for printing press beds, comprising a base, members slidably mounted on the base and extending at right angles thereto, the members being adjustable toward or from each other, fingers 60 carried by the base and by said members, said fingers on the base being adjustable longitudinally therealong and the fingers on said members being adjustable along said members in a direction at right angles to the 65 direction of adjustment of the fingers on the base, all of said fingers being mounted for movement into or out of a parallel relation to the part upon which the fingers are mounted and means holding the fingers in 70 adjusted position.
2. A device of the character described comprising a supporting member, a taut wire extending longitudinally of the supporting member and engaged therewith, 75 its ends, slides mounted upon the supporting member and over which the wire passes, fingers carried by the slides, and means for tensioning the wire to clamp the slides in adjusted position.
3. A device of the character described comprising a supporting member, a taut wire extending longitudinally of the supporting member and engaged therewith at 80 its ends, slides mounted upon the supporting member and over which the wire passes, fingers carried by the slides, and means for tensioning the wire to clamp the slides in adjusted position, said means comprising a 85 rod passing through the supporting member and having an eye engaging with said wire, and a lever pivoted upon the supporting member and with which the end of the rod is pivotally engaged, said lever when thrown into one position tightening the wire and 90 when shifted to another position slackening the wire.
4. A device of the character described comprising a longitudinally extending slotted bar, a wire extending along the inner 95 edge face of said bar but spaced therefrom, a pair of slides having tongues, the slides being disposed between the wire and the face of the bar and the bar being longitudinally slotted to receive the tongues, fingers pivotally mounted upon the slides, means for tensioning the wire, to thereby increase the 100 pressure on the slides and hold the slides in adjusted positions, a pair of grippers mounted upon the bar and having bolts extending into said slot of the bar whereby the grippers may be shifted nearer to or farther from each other, the grippers extending normally at right angles to the bar, a longitudinally extending wire mounted upon but disposed in spaced relation to the inner edge 105 face of each gripper, slides mounted between said wire and the inner face of each gripper, pivoted gripping fingers mounted upon said slides, and means for increasing or decreasing the tension of said wire to thereby hold the slides in adjusted positions, or release the slides to permit of their longitudinal adjustment.
5. In a device of the character described, 110 a member having a longitudinally extending edge groove, a wire extending parallel to but in spaced relation to the inner edge face of the member, means engaging the middle of the wire for drawing the middle of the wire toward the member, or releasing the tension on the wire, a slide disposed between the wire and the inner edge face of the member and having a tongue engaging in the groove, the wire engaging the outer face of said slide, a gripping finger pivotally mounted 115 upon said slide for movement into or out of parallel relation to the first named member, and a spring holding the gripping finger in a position parallel to the first named member or at right angles thereto.
6. A device of the character described comprising a longitudinally slotted supporting bar formed upon its upper face with a longitudinally extending groove, grippers disposed upon the face of the bar and having 120 tongues engaging in the groove, bolts passing through said grippers and through the slot of the bar whereby the grippers may be adjusted along the bar, gripping fingers slidably mounted upon the bar and pivotally 125 supported for movement into or out of a position at right angles to the bar, and gripping fingers slidably mounted upon the grippers and pivotally supported for movement into or out of position at right angles to the 130 grippers.

In testimony whereof I hereunto affix my signature in the presence of two witnesses.
